UNITED STATES PATENT OFFICE.

JOHN CHARTER, OF STERLING, ILLINOIS.

GAS-ENGINE.

SPECIFICATION forming part of Letters Patent No. 292,894, dated February 5, 1884.

Application filed April 19, 1883. (No model.)

To all whom it may concern:

Be it known that I, JOHN CHARTER, a citizen of the United States, residing at Sterling, in the county of Whiteside and State of Illinois, have invented certain new and useful Improvements in Gas-Engines; and I do hereby declare the following to be a full, clear, and exact description of the invention, such as will enable others skilled in the art to which it applies to make and use the same, reference being had to the accompanying drawings, and to letters or figures of reference marked thereon, which form a part of this specification.

My invention pertains to that class of engines which are operated by a mixture of gas and air, and embraces novel mechanism for the use of such mixture as such motor.

In the drawings, Figure 1 is a vertical sectional view of a machine embodying my invention, taken in the line $x-x$ of Fig. 2. Fig. 2 is a plan sectional view of the same in the line $x-x$ of Fig. 1. Fig. 3 is a plan sectional view of the same in the same plane as that of Fig. 2, but with the parts in different relation. Fig. 4 is a transverse sectional elevation of the devices for admitting the gas and air. Fig. 5 is a like view of the exhaust-port and adjacent parts. Fig. 6 shows the construction and location of the valve d' for the admission of air to the recess b for scavenger purposes.

A is the base of the engine, furnishing a support generally and fulcrums at different points, as shown.

35 B is a cylinder, within which the processes of both compression and explosion occur.

C is a working-piston acted upon by the explosion, and which communicates power to the shaft D through the medium of the piston-rod D', which latter is pivotally attached at its inner end to the piston C, and at its outer end clasps the crank E of the shaft D, and thereby revolves the latter. The shaft D is provided with the usual elbow-crank, E, near its center, and with the usual fly-wheel, F, and to such shaft the machinery to be driven by the engine can be attached in any suitable way. The piston C, in addition to communicating power, performs also the function of compressing the gaseous compound prior to explosion, and, in conjunction with the trans-

ferrer G, the further purpose of expelling the products of combustion after the explosion has occurred, as hereinafter explained.

G is a transerrer, which acts reciprocally 55 in the cylinder B at the end of the latter opposite to that traversed by the piston C.

Referring to the drawings, Fig. 1 represents the respective positions of the piston C and transerrer G at the moment explosion takes 60 place. It will be observed that in the position last named the transerrer G is at the limit of its outstroke and the piston C at the limit of its instroke. The crank E in this figure is at its inmost limit and on the plane 65 of the piston-rod D'. Between the opposing faces of the transerrer G and piston C is the compressed charge preparatory to ignition. In Fig. 3 the explosion has taken place and the piston C been driven to the limit of its 70 outstroke, rotating the shaft D one-half of a revolution. As the shaft D, by the momentum communicated to it from the fly-wheel F, completes the next succeeding quarter of a revolution, it carries the piston C to the position shown in Fig. 2. The quarter-revolution 75 last named of the shaft D, by means of intermediate mechanism hereinafter specified, has also driven the transerrer G to the limit of its instroke, the opposing faces of such 80 transerrer G and piston C being almost in contact, as shown in Fig. 2, or near enough to expel the products of combustion from the cylinder B through the exhaust-port a. After the explosion of the gaseous mixture and the resultant position of the parts, as shown in Fig. 3, 85 that portion of the cylinder B between the opposing faces of the transerrer G and piston C was filled with the residuum of combustion, which, of necessity, must be expelled before 90 such space can be occupied by the succeeding charge of explosive compound. This is accomplished by the mutual approach of the transerrer G and piston C before referred to, and as shown in Fig. 2. Such mutual approach 95 of the opposing faces aforesaid forces the interposed products of combustion through the exhaust-port a. This process is aided and rendered more effectual by the following supplemental provision: An annular recess, b, is 100 formed in the interior wall of part of the cylinder B traversed by the transerrer G. A

short tube, *e*, outside of and parallel with the cylinder *B*, communicates at one end with the recess *b* and at its other end with the cylinder *B*, in front of the transferrer *G* and near the 5 inmost limit of the latter. An inwardly-opening automatic valve, *d'*, (see Fig. 6,) is seated at the outer end of the tube *e*, and the latter has, through the seat *d''* of such valve, communication with the outer air. An automatic 10 check-valve, *d*, opening toward the center of the cylinder *B*, is placed in the tube *e*, near the inner end of the latter. The outer end of the transferrer *G* fills the annular recess *b*, and as the opening from the tube *e* into the recess *b* 15 is near the inner end of the latter, the trans- ferrer *G* in its outstroke immediately uncovers such opening, and in its outward passage fills the recess *b* with outer air drawn through the valve *d'*, the valve *d* having meanwhile cut off 20 communication at the other end of the tube *e*. As the transferrer *G* makes its instroke, the pressure of the air in the recess *b* closes the valve *d'* and opens the valve *d*, and the outer head of the transferrer *G* filling the annular 25 recess *b*, as aforesaid, the instroke of such trans- ferrer forces the pure air which filled the re- cess *b* through the tube *e* into the cylinder *B*, in front of the transferrer *G*, and out of such cylinder through the exhaust-port *a*. It is ob- 30 vious that the expulsion of the air which passes from the tube *e* into the center of the cylinder *B* is forced from the latter and out through the exhaust-port *a* by the joint action of the enlarged head of the transferrer *G* and 35 the inner face of the latter, so that such pro- cess is greatly hastened. By the use of the air-chamber *b*, as aforesaid, and the passage through the same of fresh air, I am enabled to keep that part of the cylinder *B* and the trans- 40 ferrer *G* sufficiently cool without a water- jacket. The fresh air forced from the recess *b* into the cylinder *B* and out therefrom through the exhaust *a* assists to cool such parts, drives out the products of combustion, and extin- 45 guishes any fire remaining in the residuum of the gas employed. Another advantage of the recess *b* is that it increases the capacity of the cylinder *B* behind the transferrer *G* in the pro- cess of drawing in the next charge of mixed 50 gas and air, thus giving a larger area to the lineal foot than the explosive and compression portions of the cylinder *B*, and rendering it feasible to give the transferrer *G* a short stroke, and yet draw in behind it a charge sufficient 55 to fill the space between the transferrer *G* and piston *C* when both of the latter are at the limits, respectively, of their outstroke. The same inward movement of the transferrer *G*— *i. e.*, from the position shown in Fig. 3 to that 60 shown in Fig. 2—and which assisted the piston *C*, as aforesaid, in driving out the products of the next previous combustion, serves also to draw in behind the transferrer *G*, through the inlet *H*, a charge of mixed air and gas for the 65 next explosion.

H is an inlet-port, Fig. 4, through which the

gaseous mixture is admitted into the cylinder *B*. An automatic inwardly-opening valve, *H'*, is seated in the bottom of the inlet *H*, and opens and closes the air-tube *H²* and gas-tube *H³*, surrounding the air-tube *H²*. Gas is ad- mitted into the gas-tube *H³* through a lateral opening, *H⁴*, therein.

The exhaust-port *a* has seated therein a posi- tive inwardly-opening valve, *a'*, (see Fig. 5,) 75 which latter is actuated by a lifting-spur, *a²*, on the rock-shaft *a³*. The rock-shaft *a³* is os- cillated by the rod *I*, having a crank-connec- tion therewith, and eccentrically collared at its other end on the shaft *D*; or such rock-shaft 80 *a³* may be oscillated by attachment in any suit- able way to other parts of the machine. While the shaft *D* is completing the last quarter of its revolution, so as to return to the position shown in Fig. 1—that of preparation for ex- 85 plosion—two processes are taking place in the cylinder *B*. First, the transferrer *G* forces the gaseous mixture from behind such trans- ferrer, through the tube *g*, to its front, the tube *g* 90 having, as shown in Fig. 3, the ports *h* and *h'* communicating with the cylinder *B*. The other process, which takes place during the transition of the parts from the positions shown in Fig. 2 to that shown in Fig. 1, is that 95 the piston *C*, in following the transferrer *G* inward, compresses against the inward face of the latter the charge in readiness for the next 100 explosion. By the use of mechanism herein- after described, the recession last named of the transferrer *G* is more rapid than the last 105 half of the instroke of the piston *C*, where- 110 by room is made between the opposing faces of such transferrer and piston for the admis- sion of a portion of the gaseous mixture be- 115 fore such transferrer has completed its out- stroke; and as the compression exerted by the incoming piston *C* is equal to that of the transferrer *G* on the mixture behind the lat- 120 ter, the movement of the latter and the afore- said transfer of such mixture require no more 125 force than would be necessary for compression alone. This mode economizes time and power, as the ingress or transfer of the mixture and its compression are simultaneous, and the re- 130 sult substantially of the same force. The pro- cess aforesaid of transferring the mixture is expedited and made to require less power by providing a recess, *i*, in the inner wall of the cylinder *B*, leading from the port *h* of the tube *g* to nearly the inner face of the trans- 135 ferrer *G* when at the limit of its instroke. Thus the pressure at the outer end of the latter is re- lieved before it has sensibly progressed. It will be seen that the piston *C* closes the ex- 140 haust-port *a* before the transferrer *G* lets in the 145 new charge, thus preventing the escape of any of the latter, as might be the case were the clos- 150 ing of such exhaust-port dependent solely upon the action of the valve *a'*.

K is a reciprocally-acting ignitor, which 150 plays in an enlargement and prolongation of the tube *g*, and serves also as a cut-off for the

port h' of the tube g , and is actuated by the rod K' , eccentrically collared upon the shaft D . A transverse opening, j , Fig. 3, is formed in the ignitor K , and a longitudinal hole, k , 5 extends from the opening j to the outer end of the ignitor K . In each end of the hole k are placed the flame-checks k' . A pin, k^2 , having a transverse hole, passes laterally through the ignitor K and hole k in such position as that 10 the transverse hole in the pin k^2 will be a continuation of the hole k . The ignitor K in its outstroke withdraws sufficient to uncover the port h' and to permit the passage of the gaseous mixture from behind the transferrer G 15 through the tube g into the cylinder B . The instant the latter reaches its outstroke the tube g and that portion of the cylinder B between such transferrer and the piston C are filled with the gaseous mixture under the same 20 pressure. As the ignitor K passes inward it first cuts off the passage of the mixture in the tube g through the port h' , and as the ignitor passes on to the limit of its instroke it further compresses the mixture remaining in the tube 25 g and forces the latter through the hole k . There is a piece of metal, preferably of platinum, placed in the transverse opening j , which, by the explosion, is kept at such incandescent heat as to ignite the charge in the cylinder B 30 through the opening j . Each instroke of the ignitor K , by reason of the increased compression aforesaid, fills the hole j with the gaseous mixture. An outside flame, l , communicates fire to the gaseous mixture in the hole j , 35 and the extra compression aforesaid insures the ejection of the ignited mixture into the cylinder B . I find, however, in practical use, that after a few explosions I can dispense with the outside flame, l , as the heated metal suffices for firing the charge. By turning the pin k^2 the amount of mixture passing through the hole k may be regulated.

L is a lever fulcrumed on the base A at L' , and oscillated by the rod I , eccentrically attached, as aforesaid, to the shaft D . To the upper end of the lever L is pivoted the toggle M , which latter at its opposite end is pivotally attached to the crank N of the oscillating shaft O , journaled in the supports O' , or 45 otherwise suitably supported. An elbow-crank, P , is formed in the shaft O , to which the outer end of the rod S is attached pivotally, the opposite end of the rod S being affixed to the transferrer G . The rod S is furnished 50 with the joint S' , to permit the outer end of such rod to describe the oscillations of the crank P . In Fig. 1 the lever L is shown at about five-sixths of its outward oscillation. It can readily be conceived as having passed 55 to its outer limit when the toggle M would be nearly or quite vertical. The lever L , on its return-stroke, will have proceeded so far as to have raised the toggle M to nearly the horizontal before any inward impetus will be imparted to the transferrer G , so that while the 60 lever L passes from the position shown in Fig.

1 to the verge of its outstroke and about one-fifth of the return-stroke the transferrer G remains stationary. It is during this interval that the piston C is thrown outward to its 70 outstroke by the explosion, and the advantage of the intermittent rest aforesaid of the transferrer G is that no power of the machine is lost in forcing such transferrer against the explosion, as would be the case did such transferrer 75 concurrently follow the piston C in the outstroke of the latter. When the explosion has spent its force and the piston C at the limit of its outstroke, as shown in Fig. 3, the lever L will be at about one-fifth of its instroke 80 and the toggle M nearly horizontal. During the residue of the instroke of lever L from the point last named, and until the return of such lever to the position shown in Fig. 1, such lever L and toggle M act directly upon the shaft O , 85 causing, through the medium of the rod S , the transferrer G to rapidly make a full motion and return to a momentary state of rest, as aforesaid. This full motion of the transferrer G occurs while the piston C makes its full instroke. Thereby the transferrer G , after each 90 explosion, passes into the exhaust-port a , to there meet the piston C and with the latter expel the products of combustion. The first part of the outward transit of the transferrer 95 G is the most rapid, so as to afford room between it and the piston C for the ingress of the next charge of the gaseous mixture; and while the piston C passes on from the position shown in Fig. 2 to the limit of its instroke the 100 transferrer G recedes to its outstroke—the position for explosion. As before explained, this full motion of the transferrer G not only assists to expel the residuum of combustion, but draws in and transfers the gaseous mixture, and also fills the recess b and expels the 105 air therefrom. These different functions of the transferrer G in nowise interfere with each other.

110 T is the ordinary governor, suitably connected to the gas-inlet tube H' , and arranged to cut off part or all of the gas-supply, as occasion may require.

V V are the usual annular water-jackets for cooling the piston C end of the cylinder B .

115 In my machine I dispense with cam movements in actuating the transferrer and piston, and economize both space and material by using but one cylinder for all purposes.

By varying the respective diameters of the 120 ends of the cylinder B , I can secure any desired degree of compression of the explosive mixture.

I find by actual use that my machine as herein described is a practical success.

125 What I claim as my invention, and desire to secure by Letters Patent, is—

1. In a gas-engine, the combination of the cylinder B , transferrer G , and piston C , arranged and operating substantially as shown, 130 and for the purpose described.
2. The cylinder B , provided with the annu-

lar recess *b*, the tube *e*, tube *g*, transferrer *G*, and piston *C*, arranged and operating in combination, substantially as shown, and for the purpose specified.

5 3. The transferrer *G*, in combination with the cylinder *B*, piston *C*, tube *e*, ignitor *K*, and tube *g*, substantially as shown, and for the purpose named.

4. The cylinder *B*, having the recess *b*, and 10 the tube *e*, provided with valves *d* and *d'*, and communicating at each end with the interior of such cylinder, in combination with the transferrer *G*, whereby outer air is drawn in at the 15 sides of the transferrer *G* at one stroke of such transferrer, and transmitted to the face of the latter on the opposite stroke thereof, substantially as shown, and for the purpose specified.

5. The combination of the rod *I*, lever *L*, 20 toggle *M*, shaft *O*, having crank *P*, rod *S*, and transferrer *G*, substantially as shown, and for the purpose herein named.

6. The cylinder *B*, having inlet-port *H*, tube *g*, having communications *h* and *h'* with 25 such cylinder, and the transferrer *G*, in combination, substantially as shown, and for the purpose described.

7. The cylinder *B*, having the recess *i* and inlet-port *H*, the tube *g*, having communications *h* and *h'* with such cylinder, and the transferrer *G*, in combination, substantially as 30 shown, and for the purpose specified.

8. The tube *g*, having ports *h* and *h'*, ignitor *K*, having hole *k*, and transverse hole *j*, arranged

to register with the port *h'* and cylinder *B*, in 35 combination, substantially as shown, and for the purpose herein described.

9. In a gas-engine, the rod *I*, lever *L*, toggle *M*, shaft *O*, and rod *S*, substantially as shown, by means of which the transferrer *G* is operated in the same cylinder with the piston *C*, and such transferrer is caused to make a full motion during the inward stroke of said piston *C*, whereby such transferrer alternately expels the residuum of explosion and 45 charges the working-cylinder.

10. In a gas-engine, shaft *D*, rod *I*, lever *L*, toggle *M*, shaft *O*, rod *S*, and transferrer *G*, in combination, substantially as shown, whereby a full motion of such transferrer, alternated with intermittent rests, is produced at each 50 revolution of the shaft *D*, for the purpose hereinbefore described.

11. In a gas-engine, the cylinder *B*, piston *C*, shaft *D*, piston-rod *D'*, rod *I*, lever *L*, toggle *M*, shaft *O*, rod *S*, and transferrer *G*, substantially as shown, whereby such transferrer, coincidently with expelling the residuum of 55 combustion, draws into the cylinder the charge for the next explosion, for the purpose specified.

In testimony whereof I affix my signature in presence of two witnesses.

JOHN CHARTER.
